UNITED STATES PATENT OFFICE.

ALEXANDER C. REID, OF GENOA, ILLINOIS, ASSIGNOR, BY MESNE ASSIGNMENTS, TO
THE HALL SWITCH & SIGNAL COMPANY, A CORPORATION OF MAINE.

SELECTIVE SIGNALING SYSTEM.

1,069,347.

Specification of Letters Patent.

Patented Aug. 5, 1913.

Application filed May 4, 1909. Serial No. 493,873.

To all whom it may concern:

Be it known that I, ALEXANDER C. REID, citizen of the United States, residing at Genoa, in the county of Dekalb and State 5 of Illinois, have invented a certain new and useful Improvement in Selective Signaling Systems, of which the following is a full, clear, concise, and exact description, reference being had to the accompanying drawings, forming a part of this specification.

My invention relates to selective systems, and has for its object the provision of a selective signaling device for a plurality of substations, all of which are united by the 15 same line circuit with the central station, the apparatus at the central station being designed to selectively operate the substation apparatus to call any desired station.

I will describe one embodiment of my invention in connection with the accompanying drawing, in which—

Figure 1 represents the central station apparatus and the apparatus at one substation; and Fig. 2 is a detail view of the 25 central station calling mechanism.

Referring more particularly to Fig. 1, I have shown a central station A and substation B. The apparatus at the central station is designed to send short or long impulses over the line wires 1 and 2. For 30 this purpose, I employ a plurality of wheels, 3, 4, 5, which are provided around the entire periphery with teeth 6 of uniform cross-section, each wheel also having one 35 elongated tooth 7 of considerably larger cross-sectional area, which larger tooth corresponds to the station it is desired to call. Thus, I have one wheel for each substation provided with an angularly displaced large 40 tooth 7. The wheels are all mounted on a common shaft and operate synchronously. Each wheel is also provided with a contact 45 spring 9 and a button 10, which button can be so arranged as to remain in a depressed condition unless released by the train despatcher through the agency of the groove 11. For instance, if it is desired to call the 50 station corresponding to the wheel 3, the spring 9, which is adapted to engage the wheel 3, is pressed inwardly, and the shaft 8 started to rotate.

It will be seen that on account of the teeth 6, short impulses are sent over the

line wires 1 and 2 during the entire revolution of the wheel 3, excepting when it engages the large tooth 7, when a long impulse is transmitted over said line conductors. These impulses are sent from the battery 12 through the agency of the relay 13, which may be energized by the battery 14 55 through the teeth on the wheels 3, 4, 5 and the corresponding springs 9. The wheels 3, 4, 5 and the springs 9 may be connected in parallel across the battery and the relay 13 so that only one line relay 13 is necessary. 60 Now, as before stated, the larger teeth 7, on the various wheels 3, 4 and 5, are angularly displaced so that these long impulses occur when the selective devices at the substations are in proper position to correspond, 65 so that a long impulse at a particular time from a given wheel will operate the corresponding substation signaling apparatus. Thus, when it is desired to call three or four stations, the springs 9, corresponding to the 70 wheels arranged for said substations, are pressed inwardly, and short impulses will be continually sent over the line, except at such times when the long impulses, due to the teeth 7, are transmitted from the wheel 75 selected. Under these circumstances only the desired signal will respond because when the long tooth 7 of wheel 3 is in engagement with its spring 9, its corresponding station, say station 3, only will respond 80 because the arm 25 on that station is the only one then making contact at 27. The others have either passed their contact or have not reached it.

The central station also is provided with 85 a telephone system consisting of the receiver 15, transmitter 16 and its associate apparatus. Each substation is likewise equipped. The line wires 1 and 2, as stated, lead to the various substations, and the 90 short and long impulses operate a relay 17, which relay 17, when energized, attracts its armature 18, thereby closing circuit through the relay 19 and the relay 20. The relay 19 is provided with an armature 21, 95 and when said relay 19 is energized, it attracts its armature, and upon the reversing movement of said armature, due to the spring 22, the arm 23 rotates the step-by-step element 24 one point. The step-by-step element 24 has a contact bar 25, adapted 100

to engage the contact points 26 and 27, the substation here shown being connected to the contact point 27. A locking pawl 28 is also provided. Thus a short impulse of the relay 19 will step up the device 24, bringing it into engagement with the contacts under the control of the arm 25. Now, when the step-up element reaches the associated contact 27, and it is desired to call the 10 substation B, the wheel 3, instead of sending a short impulse, is sending a long impulse, which keeps the circuit, through the contact point 27, closed a considerable length of time, thereby actuating the sluggish 15 moving element 29 through the agency of the relay 30, provided at the same time circuit is maintained through the contact springs 44. If, for instance, the contact arm 25 only contacts with the contact 20 point 27 a short period of time, and the circuit through springs 44 is also only momentarily maintained, the relay 30 has its armature attracted momentarily, and the long spring arm 31, while tending to draw 25 the sluggishly moving element 29 downwardly, has not sufficient time to do so to overcome its inertia as the armature is released before that time occurs; but if the relays 30 and 19 are held energized a con- 30 siderable length of time, the slow moving element 29 finally operates, and its circuit-closing spring 32 engages the spring 33, thereby closing a circuit through the relay 34, which operates the local signal 35. A 35 hand-switch 36 is provided, so that the signal operations of the signal may be stopped. The relay 30 receives its current from the battery 37, and the relay 34 from the battery 38. If, however, the element 24 happens to be stopped to engage contact point 40 27, and the armature of relay 19 does not remain in its attracted position, relay 30 is not energized and its local signal will not respond. Thus, it will be seen that if the 45 contact point 27 is merely passed by a short impulse, the substation B is not called, but if a long impulse occurs to maintain the contact with the element 27, and through the springs 44, the said substation B is called. 50 An induction coil having the primary winding 39 is included with the signal 35, the secondary 40 of which is bridged through the interposition of a condenser 41 to the line conductors 1 and 2 and thereby 55 a return signal is sent to the central station. When the step-by-step element 24 comes back to its normal position, a big 42 opens contact through the spring 43, to open the circuit through the secondary winding 40, 60 and to prevent further return signals. As has been stated before, the circuit through the relay 30 is also completed through the springs 44, which maintain this circuit closed a long period of time when a long im- 65 pulse is coming over the line.

As before stated, when the relay 19 operates, the relay 20 also operates, and the first impulse of the relay 20 actuates its armature and releases the clock mechanism 45, having the contact arms 46, 46, and which clock mechanism begins to travel contra-clockwise until the lug 47 again engages the arm 48. The clock mechanism, is designed so that the speed of its rotation is such as to bring the contact arm 46 into engagement with the pin 49, after the step-up element 24 has completed its operations, and immediately upon closing contact with the pin 49, circuit is closed through the battery 37, and the relay 50, which permits said relay 50 to actuate its armature, and thereby to release the arms 23 and 28, so that the step-up element can return to its normal position. In the meantime, the rotation of the clock mechanism 45 is continued past the contact-making position, when it is again held through the agency of the lug 47. 70 75 80 85 90

While I have herein shown and particularly described the preferred embodiment of my invention, I do not wish to limit myself to the precise construction and arrangement as herein set forth, but 95

Having thus set forth its most salient features, what I claim as new and desire to 95 secure by Letters Patent is:

1. A selective signaling system comprising a central station and a plurality of substations, a step-by-step selector at each substation, a signal under the control of said selector, a sluggishly moving circuit-closing element interposed between said step-by-step element and said signal, adapted to place said signal in operative condition when said step-by-step element remains in a circuit closing position a longer period of time than is required to effect an operative movement of said selector, a relay for operating said step-by-step selector, and switching means operating conjointly with each operation of said relay in circuit with the circuit-closing portion of said step-by-step element. 100 105 110

2. A selective signaling system comprising a central station and a plurality of substations, a step-by-step selector at each substation, calling devices at the central station, an automatic release mechanism for each step-by-step selector, a local signal adapted to operate independently of said selector after being placed in operative condition thereby, means for sending a return indication to the central station from said operating signal, and instrumentalities for stopping the operative actuation of said means independently of said signal, when the selector is restored to normal. 115 120 125

3. A signaling system having a central station and a plurality of substations, a step-by-step selector at each substation, a 130

signal under the control thereof, means controlled at the central station for selecting any desired signal for operation through the agency of said step-by-step apparatus, a 5 return signal device associated with each signal and adapted for operation conjointly with the operations of said signal, and automatic means for interrupting the return sig-

nal indications irrespective of the operating signal. 10

In witness whereof, I hereunto subscribe my name this 5th day of March A. D., 1909.

ALEXANDER C. REID.
